UNITED STATES PATENT OFFICE.

SAMUEL W. BROWN, OF KLINGERSTOWN, PENNSYLVANIA.

RAIL-JOINT.

1,157,145.

Specification of Letters Patent.

Patented Oct. 19, 1915.

Application filed March 24, 1915. Serial No. 16,587.

To all whom it may concern:

Be it known that I, SAMUEL W. BROWN, a citizen of the United States, residing at Klingerstown, in the county of Schuylkill and State of Pennsylvania, have invented 5 certain new and useful Improvements in Rail-Joints, of which the following is a specification.

My invention relates to improvements in 10 rail joints, the object of the invention being to provide improved means for joining the ends of rails which dispenses altogether with the employment of bolts and nuts, and which securely holds the rails against 15 movement and supports them on the ties.

A further object is to provide an improved construction of rail supporting chair having integral laterally projecting members positioned in openings in the webs of 20 the rails, and securely held by means of the ordinary spikes which perform the double function of preventing movement of the chair or rails relative to each other, and also prevent movement of either the chair or 25 the rails on the ties.

With these and other objects in view, the invention consists in certain novel features of construction and combinations and arrangements of parts as will be more fully 30 hereinafter described and pointed out in the claims.

In the accompanying drawings: Figure 1 is a plan view illustrating my improved rail joint. Fig. 2 is a view in side elevation of 35 Fig. 1. Fig. 3 is a view in transverse section on the line 3—3 of Fig. 1. Fig. 4 is a plan view showing the rail supporting chair positioned at an angle to the rails to illustrate the manner of assembling the parts, and 40 Fig. 5 is a perspective view of my improved rail supporting chair.

1, 1, represent the meeting ends of rails which are connected by my improved rail supporting chair 2, the latter located upon 45 ties 3, and secured by spikes 4 to the ties.

The chair 2 comprises a base plate 5 having oppositely positioned integral brackets 6, and while, of course, I am not limited to the particular number of such brackets, I 50 preferably employ four, two of said brackets extending to one side of the plate, and the other two to the opposite side of the plate, said brackets having a staggered arrangement so that no two are in transverse 55 alinement as shown in Figs. 1 and 4.

Each bracket is provided on its inner end

with a lug 7, which is adapted to enter an opening 8 in the web 9 of rails 1. It will be noted that these openings 8 are elongated so as to compensate for contraction and expansion of the rails, and also to allow a certain amount of movement of the lugs in the openings for the assembling and disconnecting of the parts.

Each rail end 1 is engaged by two lugs 7, 65 and the brackets supporting the lugs are oppositely positioned so that the end face of one bracket bears against one face of the web of the rail, and the other bracket has its inner face bearing against the opposite 70 face of the web of the rail, so that the rail is securely braced against movement in either direction. Furthermore, the base flanges 10 of the rails are recessed as shown at 11, so that they receive the brackets 6, and 75 it will be noted particularly by reference to Figs. 3 and 5, that the brackets are cut under or recessed as shown at 12 to accommodate the base flanges of the rails and assist in holding the rails against upward as well 80 as lateral displacement.

While, of course, my invention is not limited to the particular number of spikes employed, nor to their precise arrangement, I believe that four spikes will in most cases 85 amply secure the parts, and by arranging them as shown in Fig. 1, they not only secure the rails to the chair, but also secure the chair to the ties, and I provide in the base plate 5 of the chair, openings 13 to receive 90 the spikes 4.

The spikes 4 as shown in Fig. 1 prevent the rails or the chair from angular movement such as indicated in Fig. 4, and when it is desired to remove and replace a rail, it 95 is necessary first to remove the spikes and then turn the chair at an angle relative to the rails as shown clearly in Fig. 4. This movement of the chair serves to withdraw the lugs 7 from the openings 8, and a continued movement of the chair will move the brackets and lugs from above the base flanges of the rails, so that the rails can be elevated without lifting the chair. It will therefore be noted that in order to assemble 100 or disconnect the parts, it is simply necessary to position the chair at an angle to the rails, and then by turning the chair until it moves into alinement with the rails, the lugs 7 can be positioned in the openings 8 110 and will securely hold the rails.

When the spikes 4 are in position, the

2
chair and rails are prevented movement either together or independently of each other, so that the rails are securely held against movement in any direction except a sufficient amount of longitudinal movement to compensate for expansion and contraction.

Various slight changes might be made in the general form and arrangement of parts 10 described without departing from my invention, and hence I do not limit myself to the precise details set forth, but consider myself at liberty to make such changes and alterations as fairly fall within the spirit 15 and scope of the appended claims.

Having thus described my invention, what I claim as new and desire to secure by Letters Patent is:

1. In a rail joint, the combination with 20 two rails located end to end and having openings in their webs, of a chair supporting both rails, said chair having a pair of brackets at each end, the brackets of each pair reversely positioned and located out of alignment with each other, said brackets at their inner ends bearing against the webs of the rails, and having lugs thereon projected into the openings in the webs of the rails, substantially as described.

2. In a rail joint, the combination with 30 two rails located end to end and having openings in their webs, of a chair supporting both rails, said chair having a pair of brackets at each end, the brackets of each 35 pair reversely positioned and located out of alignment with each other, said brackets at their inner ends bearing against the webs of the rails, and having lugs thereon projected into the openings in the webs of the rails, 40 and said rails having recesses in their base flanges receiving the brackets, substantially as described.

3. In a rail joint, the combination with 45 two rails located end to end and having openings in their webs, of a chair supporting both rails, said chair having a pair of brackets at each end, the brackets of each 50 pair reversely positioned and located out of alignment with each other, said brackets at their inner ends bearing against the webs of the rails, and having lugs thereon projected into the openings in the webs of the rails, 55 said chair adapted to be turned to a position at an angle to the rails to release the lugs from the rails, substantially as described.

4. In a rail joint, the combination with 60 two rails located end to end and having

openings in their webs, of a chair supporting both rails, said chair having a pair of brackets at each end, the brackets of each 60 pair reversely positioned and located out of alignment with each other, said brackets at their inner ends bearing against the webs of the rails, and having lugs thereon projected into the openings in the webs of the rails, 65 said rails having recesses in their base flanges receiving the brackets, said chair adapted to be turned to a position at an angle to the rails to release the lugs from the rails, substantially as described. 70

5. In a rail joint, the combination with two rails located end to end and having openings in their webs, of a chair supporting both rails, said chair having a pair of brackets at each end, the brackets of each 75 pair reversely positioned and located out of alignment with each other, said brackets at their inner ends bearing against the webs of the rails, and having lugs thereon projected into the openings in the webs of the rails, 80 said rails having recesses in their base flanges receiving the brackets, said chair adapted to be turned to a position at an angle to the rails to release the lugs from the rails, said chair having spike receiving openings there- 85 in adapted to receive spikes bearing against the base flanges of the rails securing the chair against movement, and the rails against movement relative to the chair, substantially as described. 90

6. In a rail joint, the combination with two rails located end to end and having openings in their webs, of a chair supporting both rails, said chair having a pair of brackets at each end, the brackets of each 95 pair reversely positioned and located out of alignment with each other, said brackets at their inner ends bearing against the webs of the rails, and having lugs thereon projected into the openings in the webs of the rails, 100 said rails having recesses in their base flanges receiving the brackets, said chair adapted to be turned to a position at an angle to the rails to release the lugs from the rails, said openings in the webs of the rails elongated 105 longitudinally of the rails, substantially as described.

In testimony whereof I have signed my name to this specification in the presence of two subscribing witnesses.

SAMUEL W. BROWN.
